UNITED STATES PATENT OFFICE

165,046

TANDEM DISK HARROW

Harold G. Bailey, Berkley, Mich., assignor to
Dearborn Motors Corporation, Detroit, Mich., a
corporation of Delaware

Application April 30, 1949, Serial No. 2,359

Term of patent 14 years

(Cl. D39—1)

To all whom it may concern:

Be it known that I, Harold G. Bailey, a citizen of the United States, and a resident of the city of Berkley, in the county of Oakland, and State of Michigan, have invented a new, original, and ornamental Design for a Tandem Disc Harrow, of which the following is a specification, reference being had to the accompanying drawings, forming a part thereof.

In the drawings:

Fig. 1 is a side perspective view of a tandem disc harrow showing my new design; and

Fig. 2 is a top plan view thereof.

The characteristic features of my design reside in the configuration of the frame, in the manner in which the frame members are ar-

ranged and in their relationship with the disc gangs all as shown.

I claim:

The ornamental design for a tandem disc harrow, as shown and described.

HAROLD G. BAILEY.
